FIG. 2.

FIG. 3.

INVENTOR

Rudolph A. Schwahn

UNITED STATES PATENT OFFICE.

RUDOLPH A. SCHWAHN, OF EAU CLAIRE, WISCONSIN.

DESIGN FOR A SHIELD-BUCKLE.

50,633.

Specification for Design.

Patented Apr. 17, 1917.

Application filed January 5, 1917. Serial No. 140,837. Term of patent 14 years.

To all whom it may concern:

Be it known that I, RUDOLPH A. SCHWAHN, a citizen of the United States, residing at Eau Claire, in the county of Eau Claire and State of Wisconsin, have invented a new, original, and ornamental Design for a Shield-Buckle, of which the following is a specification, reference being had to the accompanying drawings, forming a part thereof.

Figure 1 is a plan view of a shield buckle showing my new design.

Fig. 2 is another plan view taken from the opposite side thereof.

Fig. 3 is a side elevational view of the design.

I claim:

The ornamental design for a shield buckle, as shown.

RUDOLPH A. SCHWAHN.

Witnesses:

B. R. SCHWAHN,
DOROTHY I. PATRIE.
